UNITED STATES PATENT OFFICE.

FRANK HAHN AND JOHN HAHN, OF DECATUR, ILLINOIS.

DOOR-OPERATED ALARM DEVICE FOR MAIL-BOXES.

No. 839,137.

Specification of Letters Patent.

Patented Dec. 25, 1906.

Application filed April 30, 1906. Serial No. 314,560.

To all whom it may concern:

Be it known that we, FRANK HAHN and JOHN HAHN, citizens of the United States, residing at Decatur, in the county of Macon and State of Illinois, have invented certain new and useful Improvements in Door-Operated Alarm Devices for Mail-Boxes; and we do hereby declare the following to be a full, clear, and exact description of the invention, such as will enable others skilled in the art to which it appertains to make and use the same.

The principal object of our invention is the provision of an exceedingly simple and efficient construction of automatic door-operated mail-box alarm device—that is to say, an alarm device automatically actuated by the raising of the lid or cover or door of the mail-box in the act of the postman depositing mail in the box, whereby the occupants of the house are notified immediately by audible signal of the fact that mail is awaiting them.

It is a further and important object of our invention to provide a peculiar form of mail-box in connection with our simple and compact alarm mechanism, whereby they may be readily installed and removed at will by even the most unskilled persons without injuring the house to which our device may be attached.

With these objects in view and others appearing as the specification proceeds our invention comprehends the novel construction, combination, and arrangement of parts of a device characterized by our invention, as will be hereinafter fully detailed in the specification, summed up in the claims, and illustrated in the drawings, in which—

Figure 1 is a perspective view of our improved form of mail-box and alarm mechanism installed for use. Fig. 2 is a perspective detail of our mail-box, the lid or cover thereof being raised. Fig. 3 is a detail rear elevation of the plate carrying the alarm mechanism. Fig. 4 is a side elevation thereof with the bell thereon.

Referring to the drawings in detail, A designates a mail-box which may be formed as shown—that is, oblong in exterior contour, with a rear supporting plate or side a extending beyond the top and bottom ends of the box and provided with means permitting attachment to a door-jamb b , as with perforations a^2 ; with a hinged cover or lid a^3 , carrying fast thereon a rock-shaft a^4 , extending

through the door-jamb b ; with a curved shield a^5 depending from the top of the front side a^6 of the box, so that mail deposited in the box may not be removed by unauthorized persons, and with a hinged door a^7 , normally locked, whereby access may be had to the mail deposited in the box.

To the rear side of the door-jamb b , and consequently within the house and in alignment with the mail-box lid a^3 , is secured, as by screws b^2 , a preferably annular ring or plate B, provided with a cross-piece b^3 , through which the square inner end of the rock-shaft a^4 projects, as shown clearly in Figs. 3 and 4.

Secured on the square inner end of the rock-shaft a^4 is a rack-plate b^4 , meshing with a small pinion b^5 , fast on a shaft b^6 , journaled in the plate or cross-piece b^3 . The shaft b^6 has also fast thereon a large toothed wheel b^7 , meshing with a pinion b^8 , fast on a shaft b^9 , journaled in the cross-piece b^3 . On the outer end of the shaft b^9 is secured a cross-piece b^{10} , pivotally carrying at each end a clapper b^{11} .

Rising from the edges of plate or ring B are standards b^{12} , converging and meeting at their tops. A semicircular or elliptical bell-plate b^{13} or cup is disposed over the standards b^{12} , as shown in Fig. 4, and suitably secured thereon, as by a set-screw b^{14} , as seen in Fig. 5.

The operation is obvious: The postman in the act of lifting the lid a^3 to deposit mail in the box will cause the rock-shaft a^4 , fast on the lid a^3 , to rock the rack-plate b^4 , turning the small pinion b^5 in mesh therewith, which in turn rotates the shaft, and consequently the large toothed wheel b^7 , fast thereon, which will rotate the pinion b^8 in mesh with the wheel b^7 , thus rotating the shaft b^9 , fast on the pinion b^8 , and swinging the cross-piece b^{10} to bring the clappers b^{11} into contact with the bell b^{13} . A half-turn of the lid a^3 of the mail-box will result in revolving the clappers at least six or seven times into contact with the bell, thus insuring that the audible alarm will be heard.

One advantage of our construction is that to install the same no marring or injuring of the door-jamb or other part of the house will result, as only a small hole for the rock-shaft a^4 will have to be bored or drilled through the door-jamb b , and as the mail-box is constructed of very light thin material (preferably tin) only very small screws are necessary to hold the same against the door-jamb. Another important advantage of our con-

struction is that the mail-box and the alarm mechanism are exceedingly easy of installation and removal when desired. All that is necessary to be done when it is desired to remove the mail-box and the alarm device is to unscrew the screws b^2 and b^{14} , which will release the bell and the alarm mechanism, and then to unscrew the screws securing the mail-box A to the door-jamb. The operation of installation is of course the reverse of the operation just described. The simplicity of this arrangement and operation is apparent.

Having thus fully described our invention, what we claim as new, and desire to secure by Letters Patent, is—

1. In door-operated alarm devices for mail-boxes, a mail-box adapted to be secured to the jamb of a door, and having a hinged cover or lid, a rock-shaft fast on the cover and adapted to extend through the door-jamb, a plate adapted to be secured to the inside of the door-jamb and through which the end of the rock-shaft projects, said plate being formed with standards rising therefrom and converging and meeting at their tops, a curved bell plate or cup secured to the standards, and mechanism carried by the plate and connected to the end of the rock-shaft, whereby movement of the rock-shaft brings said mechanism into contact with the bell-cup to cause an audible signal.

2. In door-operated alarm devices for mail-boxes, a mail-box adapted to be secured to the jamb of a door, and having a hinged cover or lid, a rock-shaft fast on the cover

and adapted to extend through the door-jamb, a ring adapted to be secured to the inside of the door-jamb and formed with a cross-piece through which the end of the rock-shaft projects, a curved bell plate or cup secured to the ring, and mechanism carried by the cross-piece of the ring and connected to the end of the rock-shaft, whereby movement of the rock-shaft brings said mechanism into contact with the bell-cup to cause an audible signal.

3. In door-operated alarm devices for mail-boxes, a mail-box adapted to be secured to the jamb of a door, and having a hinged cover or lid, a rock-shaft fast on the cover and adapted to extend through the door-jamb, a ring adapted to be secured to the inside of the door-jamb and provided with a cross-piece and formed with standards or upward-extending arms, a curved bell plate or cup secured to the standards, and mechanism carried by the cross-piece of the ring and connected to the end of the rock-shaft, whereby movement of the rock-shaft brings said mechanism into contact with the bell-cup to cause an audible signal.

In testimony whereof we affix our signatures in the presence of two subscribing witnesses.

FRANK HAHN.
JOHN HAHN.
